UNITED STATES PATENT OFFICE.

RUDOLPH VESELY, OF CHICAGO, ILLINOIS.

DESIGN FOR AN EDIBLE CANDY OR CAKE CONFECTION.

59,993.

Specification for Design.

Patented Dec. 13, 1921.

Application filed May 7, 1921. Serial No. 467,575. Term of patent 14 years.

To all whom it may concern:

Be it known that I, RUDOLPH VESELY, a citizen of Czecho-Slovakia, residing at Chicago, in the county of Cook and State of Illinois, have invented a new, original, and ornamental Design for an Edible Candy or Cake Confection, of which the following is a specification, reference being had to the accompanying drawings, forming part thereof;

Fig. 2 is a side elevation of the same;

Fig. 3 is a top plan view; and

Fig. 4 is a sectional view of the showing of Fig. 2.

I claim:

The ornamental design for an edible candy or cake confection, as shown.

In testimony whereof, I have hereunto signed my name in the presence of two subscribing witnesses.

RUDOLPH VESELY.
